UNITED STATES PATENT OFFICE.

JAMES K. DIAMOND, OF GRAND RAPIDS, MICHIGAN, ASSIGNOR TO CLIPPER BELT LACER COMPANY, OF GRAND RAPIDS, MICHIGAN.

MACHINE FOR APPLYING BELT FASTENERS AND THE LIKE.

Application filed April 29, 1926. Serial No. 105,424.

The main objects of this invention are:

First, to provide an improved machine for applying belt fasteners to belts and the like which is very powerful.

5 Second, to provide an improved fastener applying machine by means of which a plurality of hooked fasteners are set into a belt with a minimum of cutting action on the belt and in such a manner as to utilize the 10 full pulling power or strength of the fastener.

Third, to provide an improved fastener applying machine which may be adjusted to operate with substantially the same efficiency 15 on various thicknesses of belts and sizes of fasteners.

Fourth, to provide an improved fastener applying machine having these advantages which is very easy to operate.

20 Objects pertaining to details and economies of construction and operation of the invention will definitely appear from the detailed description to follow. The invention is clearly defined and pointed out in the 25 claims.

A structure embodying the features of my invention is clearly illustrated in the accompanying drawing forming a part of this application, in which:

30 Fig. 1 is a perspective view of a machine embodying the features of my invention, a fragment only of the supporting table or bench being shown.

Fig. 2 is a detail view partially in vertical 35 section on a line corresponding to broken line 2-2 of Fig. 4.

Fig. 3 is a detail view partially disassembled and partially in section on a line corresponding to the broken line 3-3 of Fig. 5.

40 Fig. 4 is a detail view partially in vertical section on a line corresponding to line 4-4 of Figs. 2 and 5.

Fig. 5 is a detail view partially in horizontal section on a line corresponding to line 5-5 of Figs. 2 and 4.

Fig. 6 is an enlarged fragmentary view showing the relation of the fasteners to the belt to which they are to be applied with the jaws in open position.

50 Figs. 7 and 8 are fragmentary views of parts shown in Fig. 6 showing successive steps in the closing of the jaws.

Fig. 9 is a fragmentary view showing the jaws completely closed.

55 Fig. 10 is a fragmentary view showing one

of the fasteners set into or secured to the belt.

Referring to the drawing, 1 represents the supporting bed or table top. On this I mount the base brackets 2 which carry the base rods 3. These base rods have nuts 4 threaded upon 60 each end thereof. Centrally on these rods I mount a pair of uprights 5 having opposed vertical ways 6 on their inner sides and vertical slots 7 in their upper ends. The base rods 3 also carry the jaw supports 8 which are arranged in opposed pairs, the supports having tapered bores 9 to receive the rods so that the opposed pairs of jaw supports may be tilted or adjusted to and from each other.

65 The jaws are adjusted and rigidly supported in their adjusted positions by means of rods 10 which are arranged through the horizontal aligned bores 11 in the supports as shown in Fig. 5, these bores being of such size as to permit the adjustment or swinging 70 movement of the supports.

75 The rods are arranged through cross bars 12 and 13 disposed at the outer sides of the supports 8, the rods having castellated nut 14 at one end. Thrust members 15 are arranged between the nuts and the cross bars 12 and adjusting nuts 16 are arranged at the other ends at the outer side of the thrust members 15.

80 The adjusting nuts 16 are provided with sprocket wheels 17 connected by the sprocket chain 18, one of the nuts 16 having a hand-piece 19 so that the nuts are simultaneously adjusted to open and close the jaw supports. A belt tightener 20 is mounted on the cross 85 piece 13.

90 These jaw supports are provided with thrust bearing plates 21, these bearing plates being chilled or of suitable material to withstand the wear and thrust of the jaws 95 thereon.

95 The jaws 22 are provided with curved bearings 23 coacting with these bearing thrust plates. The jaws are also provided with downwardly projecting arms 24 disposed between the pairs of jaw supports. The jaws are supported with their bearings in proper relation to the thrust plates 21 by means of the holders 25 which have segmental slots 26 therein with which the pins 27 on the jaw arms engage. These holders also have curved surfaces 28 in opposed relation to the bearings of the jaws, the jaw arms having pins 29 coacting with these curved surfaces.

100 The jaws are thus supported with their 105

bearings in rocking or rolling engagement with the thrust plates on the jaw supports, substantially as though there were a rack and gear between the parts. The jaws are actuated by means of the driving pinion 30 mounted on the shaft 31 carried by the uprights and provided with a two-armed crank 32. This pinion coacts with the rack 33 carrying the cross member 34 at its end, this cross member having rollers 35 on the ends thereof coacting with the guide ways 6 of the uprights.

A thrust roller 37 is disposed in opposed relation to the pinion 30 to support the lower end of the rack, this thrust roller being mounted on a shaft 38 carried by the uprights. The cross member 34 on the rack connects the inner ends of the links 39 to the upper end of the rack, the lower ends of the links being connected to the arms 24 by means of the pivots 40. The links are arranged in pairs; that is, there is a pair on each side of the rack, thus balancing the stresses.

The jaws are provided with flat jaw faces 41 which are arranged in a plane above the axial center of the jaws or the axis about which the jaws oscillate. Below the jaw faces the jaws are provided with longitudinal recesses 42 adapted to receive the ends of the horizontal arms of the T-shaped fastener holder 43. This fastener holder has a plurality of transverse slots adapted to receive the bights of the lacing hooks 44. A locking pin 45 is arranged longitudinally of the holder to retain the fasteners in position, the locking pin engaging the bights thereof as is indicated in Fig. 6. The lower walls of the recesses 42 are, in the embodiment illustrated, in approximately the radial planes of the curved jaw bearings.

The fastener holder is yieldingly held in a central position relative to the pair of jaws by means of the spring pressed plungers 46 which are seated in bores 47 in the jaws to project through the recesses 42 into engagement with the edges of the fastener holder, the plungers being yieldingly supported by means of the springs 48.

The holder is supported against longitudinal movement in the recesses by means of the lug 49 in the bottom of one of the recesses engaging a notch 50 in the edge of the holder, see Fig. 9. The jaw supports are urged to open position by means of the coiled springs 51 arranged on the rods 10 between the uprights and the jaw supports. Washer-like thrust members 52 are arranged between the ends of the springs and the jaw supports.

With this arrangement, as the nuts 16 are rotated to open or separate the jaw supports the springs force them apart.

In use, a set of fasteners suitable for the particular thickness of the belt, are placed in the holder. The jaws are then actuated, the faces of the jaws following and supporting

the fasteners as their prongs are set or forced through the belt, indicated at 53, as shown in Figs. 6, 7 and 8. In the event the fasteners are not completely set on the first actuation of the jaws, which is usually the case, the supports are closed or adjusted closer together and the jaws are again actuated. This may be repeated until the fasteners are embedded or set as shown in Figs. 9 and 10. It will be noted that the jaws are actuated by a toggle action.

With the parts arranged as shown, a very powerful actuating means is secured. The jaws are supported so as to secure a rocking motion, swinging their faces parallel with the sides of the belt and supporting the arms of the hooks or fasteners throughout the closing movement so that the fasteners are set with their prongs in position to secure a maximum of pulling strength and without cutting or tearing the belt.

The holder is floatingly supported so that it centers itself relative to the closing of the jaws. The bearings for the jaws are arranged so that the wear and friction thereon is eliminated.

I have illustrated and described my improvements in an embodiment which has proved highly satisfactory. I have not attempted to illustrate or describe certain modifications or adaptations, as I believe the disclosure made will enable those skilled in the art to embody or adapt my improvements as may be desired.

Having thus described my invention, what I claim as new and desire to secure by Letters Patent is:

1. In a structure of the class described, the combination of spaced horizontally disposed base rods, uprights disposed centrally on said base rods, said uprights having vertical slots in their upper ends and provided with opposed inwardly facing ways, opposed pairs of jaw supports mounted on said base rods for adjustment to and from each other and provided with opposed flat thrust bearings, rods for adjustably supporting said jaw supports disposed through said slots in said uprights, adjusting nuts for said last mentioned rods provided with sprockets, a connecting chain for said sprockets, one of said nuts being provided with a hand piece, springs arranged on said last mentioned rods between said uprights and said jaw supports acting to separate said jaw supports, jaws provided with curved bearings coacting with said thrust bearings of said jaw supports and having downwardly projecting arms disposed between said jaw supports, said jaws having flat jaw faces above the planes of their axial centers and opposed longitudinal recesses below their said faces, the lower walls of said recesses being in approximately the planes of the radial centers of said jaws, means for supporting said jaws with their bearings in

rocking engagement with said thrust bearings of said jaw supports, a fastener holder disposed in said recesses, spring pressed centering plungers disposed to engage the edges of said fastener holder, a rack provided with guide members coacting with said ways of said uprights, links connecting the upper end of said rack with the lower ends of said jaw arms providing an actuating toggle for said jaws, and a driving pinion mounted on said uprights to coact with said rack.

2. In a structure of the class described, the combination of spaced horizontally disposed base rods, uprights disposed centrally on said base rods, said uprights having opposed inwardly facing ways, opposed pairs of jaw supports mounted on said base rods for adjustment to and from each other and provided with opposed flat thrust bearings, jaws provided with curved bearings coacting with said thrust bearings of said jaw supports and having downwardly projecting arms disposed between said jaw supports, said jaws having flat jaw faces above the planes of their axial centers and opposed longitudinal recesses below their said faces, the lower walls of said recesses being in approximately the planes of the radial centers of said jaws, means for supporting said jaws with their bearings in 25 rocking engagement with said thrust bearings of said jaw supports, a fastener holder disposed in said recesses, spring pressed centering plungers disposed to engage the edges of said fastener holder, a rack provided with 30 guide members coacting with said ways of said uprights, links connecting the upper end of said rack with the lower ends of said jaw arms providing an actuating toggle for said jaws, and a driving pinion mounted on said uprights to coact with said rack.

3. In a structure of the class described, the combination of spaced horizontally disposed base rods, uprights disposed centrally on said base rods, said uprights having vertical slots in their upper ends and provided with opposed inwardly facing ways, opposed pairs of jaw supports mounted on said base rods for adjustment to and from each other and provided with opposed flat thrust bearings, rods for adjustably supporting said jaw supports disposed through said slots in said uprights, adjusting nuts for said last mentioned rods provided with sprockets, a connecting chain for said sprockets, one of said nuts being provided with a hand piece, springs arranged on said last mentioned rods between said uprights and said jaw supports acting to separate said jaw supports, jaws provided with curved bearings coacting with said thrust bearings of said jaw supports and having downwardly projecting arms disposed between said jaw supports, said jaws having flat jaw faces above the planes of their axial centers, means for supporting said jaws with their bearings in rocking engagement with

said thrust bearings of said jaw supports, a fastener holder operatively associated with said jaws, a rack provided with guide members coacting with said ways of said uprights, links connecting the upper end of said rack with the lower ends of said jaw arms providing an actuating toggle for said jaws, and a driving pinion mounted on said uprights to coact with said rack.

4. In a structure of the class described, the combination of spaced horizontally disposed base rods, uprights disposed centrally on said base rods, said uprights having opposed inwardly facing ways, opposed pairs of jaw supports mounted on said base rods for adjustment to and from each other and provided with opposed flat thrust bearings, jaws provided with curved bearings coacting with said thrust bearings of said jaw supports and having downwardly projecting arms disposed between said jaw supports, said jaws having flat jaw faces above the planes of their axial centers, means for supporting said jaws with their bearings in rocking engagement with said thrust bearings of said jaw supports, a fastener holder operatively associated with said jaws, a rack provided with guide members coacting with said ways of said uprights, links connecting the upper end of said rack with the lower ends of said jaw arms providing an actuating toggle for said jaws, and a driving pinion mounted on said uprights to coact with said rack.

5. In a structure of the class described, the combination of spaced horizontally disposed base rods, uprights disposed centrally on said base rods and provided with opposed inwardly facing ways, opposed pairs of jaw supports mounted on said base rods for adjustment to and from each other and provided with opposed thrust bearings, rods for adjustably supporting said jaw supports, adjusting nuts for said last mentioned rods, means for simultaneously adjusting said nuts, springs arranged on said last mentioned rods between said uprights and said jaw supports acting to separate said jaw supports, jaws provided with curved bearings coacting with said thrust bearings of said jaw supports and having downwardly projecting arms disposed between said jaw supports, said jaws having flat jaw faces and opposed longitudinal recesses below their said faces, a fastener holder disposed in said recesses, yielding means for centering said fastener holder between said jaws, a rack provided with guide members coacting with said ways of said uprights, links connecting said rack with said jaws, and a driving pinion mounted on said uprights to coact with said rack.

6. In a structure of the class described, the combination of spaced horizontally disposed base rods, uprights disposed centrally on said base rods and provided with opposed inwardly facing ways, opposed pairs of jaw sup-

ports mounted on said base rods for adjustment to and from each other and provided with opposed thrust bearings, rods for adjustably supporting said jaw supports, adjusting nuts for said last mentioned rods, means for simultaneously adjusting said nuts, springs arranged on said last mentioned rods between said uprights and said jaw supports acting to separate said jaw supports, 10 jaws provided with curved bearings coacting with said thrust bearings of said jaw supports and having downwardly projecting arms disposed between said jaw supports, said jaws having flat jaw faces, a fastener holder operatively associated with said jaws, a rack provided with guide members coacting with said ways of said uprights, links connecting said rack with said jaw arms, and a driving pinion mounted on said uprights to 20 coat with said rack.

7. In a structure of the class described, the combination of opposed pairs of jaw supports mounted for adjustment to and from each other and provided with opposed thrust 25 bearings, rods for adjustably supporting said jaw supports, adjusting nuts for said rods provided with sprockets, a connecting chain for said sprockets so that they are simultaneously adjusted, springs arranged on said rods between said uprights and said jaw supports acting to separate said jaw supports, jaws provided with bearings coacting with said thrust bearings of said jaw supports and having downwardly projecting arms disposed 30 between said jaw supports, said jaws having flat faces above the planes of their axial centers and opposed recesses below their said faces, a fastener holder disposed in said recesses, means for yieldingly centering said 35 fastener holder between said jaws, a reciprocatingly mounted rack, links connecting said rack with said jaw arms, and a driving pinion coacting with said rack.

8. In a structure of the class described, the combination of opposed pairs of jaw supports mounted for adjustment to and from each other and provided with opposed thrust bearings, jaws provided with bearings coacting with said thrust bearings of said jaw supports and having downwardly projecting arms disposed between said jaw supports, said jaws having flat faces above the planes of their axial centers and opposed recesses below their said faces, a fastener holder disposed in said recesses, means for yieldingly centering said 45 fastener holder between said jaws, a reciprocatingly mounted rack, links connecting said rack with said jaw arms, and a driving pinion coacting with said rack.

60 9. In a structure of the class described, the combination of opposed pairs of jaw supports mounted for adjustment to and from each other and provided with opposed thrust bearings, rods for adjustably supporting said jaw supports, adjusting nuts for said rods

provided with sprockets, a connecting chain for said sprockets so that they are simultaneously adjusted, uprights disposed between the jaw supports, springs arranged on said rods between said uprights and said jaw supports acting to separate said jaw supports, jaws provided with bearings coacting with said thrust bearings of said jaw supports and having downwardly projecting arms disposed between said jaw supports, said jaws having jaw faces above the planes of their axial centers, a fastener holder operatively associated with said jaws, a reciprocatingly mounted rack, links connecting said rack with said jaw arms, and a driving pinion coacting with said rack.

10. In a structure of the class described, the combination of opposed pairs of jaw supports mounted for adjustment to and from each other and provided with opposed thrust bearings, jaws provided with bearings coacting with said thrust bearings of said jaw supports and having downwardly projecting arms disposed between said jaw supports, said jaws having flat faces above the planes of their axial centers, a fastener holder operatively associated with said jaws, a reciprocatingly mounted rack, links connecting said rack with said jaw arms, and a driving pinion coacting with said rack.

11. In a structure of the class described, the combination of opposed jaw supports mounted for adjustment to and from each other and provided with opposed thrust bearings, jaws rockingly supported to coact with said thrust bearings of said jaw supports, said jaws having flat faces above the planes of their axial centers and opposed recesses below their said faces, a fastener holder disposed in said recesses, means for yieldingly centering the fastener holder between said jaws, and means for actuating said jaws.

12. In a structure of the class described, the combination of opposed jaw supports mounted for adjustment to and from each other and provided with opposed thrust bearings, jaws rockingly supported to coact with said thrust bearings of said jaw supports, said jaws having flat faces above the planes of their axial centers, and means for rocking said jaws on said thrust bearings to open and close them.

13. In a structure of the class described, the combination of opposed jaw supports mounted for adjustment to and from each other and provided with opposed thrust bearing surfaces, jaws provided with bearings mounted to coact with said thrust bearings of said jaw supports, said jaws having flat faces above the planes of their axial centers, a fastener holder floatingly mounted between said jaws, yielding centering means for said holder, and means for actuating said jaws.

14. In a structure of the class described, the combination of opposed jaw supports

- mounted for adjustment to and from each other and provided with opposed thrust bearing surfaces, jaws provided with bearings mounted to coact with said thrust bearings of 5 said jaw supports, said jaws having jaw faces above the planes of their axial centers, a fastener holder floatingly mounted between said jaws, and means for actuating said jaws.
15. In a structure of the class described, 10 the combination of opposed pairs of jaw supports mounted for adjustment to and from each other and provided with opposed flat thrust bearings, jaws provided with curved bearings rockingly supported to coact with 15 said thrust bearings of said jaw supports, said jaws having opposed recesses, a fastener holder disposed in said recesses, means for yieldingly centering it between said jaws, and means for actuating said jaws.
20. 16. In a structure of the class described, 20 the combination of opposed pairs of jaw supports mounted for adjustment to and from each other and provided with opposed flat thrust bearings, jaws provided with curved 25 bearings rockingly supported to coact with said thrust bearings of said jaw supports, a fastener holder operatively associated with said jaws, and means for actuating said jaws.
17. In a structure of the class described, 30 the combination of opposed jaw supports mounted for adjustment to and from each other and provided with opposed flat thrust bearings, jaws provided with curved bearings mounted to coact with said thrust 35 bearings of said jaw supports, a fastener holder operatively associated with said jaws, and means for actuating said jaws.
18. In a structure of the class described, 40 the combination of opposed jaw supports provided with opposed flat thrust bearings, jaw rockingly mounted to coact with said thrust bearings of said jaw supports and having flat jaw faces above the plane of their axial centers, a fastener holder operatively associated 45 with said jaws, and means for actuating said jaws.
19. In a structure of the class described, 50 the combination of opposed adjustably mounted jaw supports, a pair of coacting jaws rockingly mounted on said supports, a fastener holder operatively associated with 55 said jaws, and means for actuating said jaws.
20. In a structure of the class described, 60 the combination of opposed jaw supports, jaws rockingly mounted on said jaw supports and having flat jaw faces above the plane of their axial centers and opposed recesses below their jaw faces, a fastener holder engaged in said recess, and means for actuating said jaws.
21. In a structure of the class described, 65 the combination of opposed adjustable jaw supports, a pair of coacting jaws rockingly mounted on said supports, a fastener holder operatively associated with said jaws, and means for actuating said jaws on said supports and independently of the adjustment of 70 said supports for opening and closing the jaws.
22. In a structure of the class described, 70 the combination of opposed jaw supporting members mounted for adjustment to and from each other, a pair of coacting rotatable jaws mounted on said supports in opposed relation, and a fastener holder carried by said 75 jaws.
23. In a structure of the class described, 75 the combination of a pair of jaw supporting members having opposed bearing faces, coacting jaws rockingly mounted on said 80 bearing faces, a fastener holder carried by said jaws, and means for simultaneously rocking said jaws to open and close them.
24. In a structure of the class described, 85 the combination of a pair of opposed jaw supporting members, means for simultaneously adjusting said members to and from each other, a pair of opposed coacting jaws provided with radially disposed jaw faces rockingly mounted on said supporting members, 90 and means for simultaneously rocking said jaws to open and close them independently of said jaw support adjustment.

In witness whereof I have hereunto set my hand.

JAMES K. DIAMOND.
